UNITED STATES PATENT OFFICE.

HENRY C. KOCH, OF UPPER YODER TOWNSHIP, CAMBRIA COUNTY, PENNSYLVANIA,
FURNACE.

1,083,500.

Specification of Letters Patent.

Patented Jan. 6, 1914.

Application filed March 21, 1913. Serial No. 755,848.

To all whom it may concern:

Be it known that I, HENRY C. KOCH, a citizen of the United States, residing in Upper Yoder township, in the county of Cambria and State of Pennsylvania, have invented certain new and useful Improvements in Furnaces; and I do hereby declare the following to be a full, clear, and exact description of the invention, such as will enable others skilled in the art to which it appertains to make and use the same.

My invention relates generally to the construction of furnaces and is especially adapted for use in connection with house heating furnaces, either hot air furnaces, hot water boiler furnaces or steam boiler heating furnaces.

My invention consists generally of a pipe or flue connection from the ash-pit of a furnace of the character described, to the lower part of the smoke flue of the same with a manually operated valve located in said pipe connection adapted to be opened and closed as desired, whereby, when the ashes are shaken down or poked from the furnace, said valve in the dust pipe connection is opened, causing a draft to pass from the ash-pit to the lower part of the smoke flue, thereby drawing off the dust and ashes into the flue, together with escaping or sulfurous gases in such a way that neither the dust, gases nor heat therefrom will escape into the furnace room or bother or dirty the operator.

By means of my invention any one is enabled to shake down the furnace without inhaling dust or gases and his person and clothes are kept clean.

In my arrangement the dust pipe leads preferably from the upper part of the ash-pit into an intermediate or lower portion of the smoke flue, which flue extends downwardly and in such a way as to make a receptacle for dust and soot, which can be withdrawn through a cleaning door at the bottom of the smoke flue extension. The lower part of the flue is preferably formed of bricks or other fireproof material and may be made larger than the upper part which carries only the smoke and combus-

tion gases, although the lower part of the said flue may be the same size as the upper part, if desired. I prefer, however, to make the lower part larger, as it gives more storage capacity for dust and soot and needs to be cleaned out only at longer intervals. There is a tight seating flap valve in the dust pipe which is preferably made of two semi-circular sections hinged on a diametral line, the hinge being made tight and the ends soldered or closed, and an abutment ring is placed in the smoke pipe, against which the valve seats tightly when closed, thereby preventing any back draft from the ash-pit to the flue when the valve is closed. When it is desired to shake the fire and drop the ashes in the ash-pit, the valve in the dust pipe is opened by means of a crank shaft to which is attached a lever, the crank of said crank shaft being connected to the semi-circular flap valves as indicated by links. The operating lever for the dust valve is provided with a convenient connection for opening it and with a weight to keep it normally in closed position.

Having thus given a general description of my invention, I will now, in order to make the matter more clear, refer to the annexed sheet of drawings which form part of this specification and in which like characters of reference indicate like parts.

Figure 1 is a side elevation of a heating furnace showing in longitudinal vertical section a portion of the ash-pit, the dust pipe, the smoke flue and the dust chamber at the lower part thereof. Fig. 2 is a longitudinal sectional plan of my dust and gas connection pipe showing the valve and operating mechanism therefor. Fig. 3 is a vertical longitudinal sectional elevation of my dust pipe showing the valve, the hinge thereof and the operating mechanism therefor.

Referring now to the various characters of reference on the drawings:—1 indicates a house heating boiler shown in this case as adapted for hot water heating. 2 is the smoke box thereof which is provided with a check draft door as shown. 3 is the smoke connection from said furnace to the smoke flue 27. 4 represents the lower part of the

said smoke flue, which, in this case, is shown of larger size and adapted to serve as a dust and soot chamber.

5 and 6 are the water-circulating pipes of the hot water boiler.

7 indicates the bottom section of the furnace in which the grates are located.

8 is the ash-pit below the furnace adapted to receive the coarse ashes and clinkers 10 which can be removed therefrom by a shovel in the usual manner through the front opening which is provided with a cover as shown.

9 is a collar or extension on the bottom section of the furnace adapted to receive the 15 dust pipe 10 which is shown in this case as cylindrical, although it may be of any other form or location as may be desired, as will be readily understood.

In the smoke pipe 10 is mounted the valve 20 11 composed of two semi-circular parts hinged at the center after the fashion of a butt or door hinge, care being taken to have this soldered or otherwise made dust and gas tight to prevent checking the draft 25 through the fire when the valve is closed. The hinge of the double flap valve 11 is provided with a pivot pin 12 and the valves when closed are seated against the angle ring 13 which is secured to the pipe 10 by riveting or soldering or otherwise as may be desired. The ends of the valves 11 are provided with looped lugs 14 to which are attached the eye links 15 which links are mounted upon the crank portion 17 of the 30 crank shaft 16, these links 15 being retained in position on the crank by collars 18 thereon provided as shown.

To the outer projecting end of the crank shaft 16 is secured the operating lever 19 40 provided with a weight 20 and a loop eye 21 which loop is secured to a flexible connection 22, which passes over the sheaves 23 and which may be secured to the hook 24 on the front of the door in a place convenient for the operator. A loop is provided in the end of the flexible connection 22 and the length is so adjusted that when said loop is hung over the hook 24 the valves 11 are wide open and when said loop is released from the hook 24 the valve is closed by the action of gravity on the weight 20.

The shaking lever for the shaking or rocking grate is indicated at 25, while 26 indicates a cleaning door at the bottom of the 55 dust chamber 4 through which fine ashes and soot may be withdrawn when required or desired.

The operation of my apparatus is as follows:—When it is desired to shake down the ashes from the furnace or to remove the 60 dusty ashes from the ash-pit, the valve 11 is opened by pulling on that part of the flexible connection 22 near the front of the furnace and putting the loop of the same

over the hook 24 or otherwise securing same. 65 The heat of the flue 27 causes a slight draft through the ash-pit, thence through the dust pipe 10 into the settling chamber 4, thereby preventing the exit of dust or ashes from the front part of the ash-pit and thus protecting the operator from offensive dust and 70 gases. After the operation of shaking the furnace or taking out the ashes is completed and the dust has settled, the valve is closed by reversing the operation just described, 75 whereupon the furnace proceeds with its operation in the regular way.

Although I have shown and described my improvements in considerable detail, I do not wish to be limited to the exact and specific details shown and described, but may use such substitutions, modifications or equivalents thereof, as are embraced within the scope of my invention or as pointed out in the claims.

Having thus described my invention, what I claim and desire to secure by Letters Patent is—

1. A heating furnace provided with a grate, an ash-pit, a main smoke flue provided with a settling chamber in the lower part thereof, a smoke connection to said main flue above the settling chamber, in combination with a pipe connecting said ash-pit with the settling chamber, a valve 90 in said pipe, means for normally holding said valve in closed position and for opening the same when desired, whereby the dust and gases from said ash-pit are drawn into and the dust deposited in the lower part or 95 settling chamber of said flue.

2. A heating furnace provided with a grate, an ash-pit below the same, a main smoke flue having a lower enlarged end forming a settling chamber, a connection 105 from the furnace fire-box to said main smoke flue, in combination with a pipe connecting said ash-pit with the settling chamber of said smoke flue, a double flap valve and seat therefor mounted in said pipe, link connections from said valves, a crank shaft mounted in said pipe to the crank portion of which said links are connected, an operating lever mounted on an outwardly projecting portion of said crank shaft and provided with a 110 weight for normally holding the valve in closed position, and flexible means connected to said lever extending to the front part of the furnace, whereby said valve may be opened and closed when desired.

3. The combination with a heating furnace provided with a shaking grate and ash-pit below the same, a main smoke flue provided with a settling chamber in the lower part thereof, a smoke connection to said flue above said settling chamber, of a pipe connecting said ash-pit with the settling chamber portion of said smoke flue, a double 125

hinged flap valve and seat therefor mounted in said pipe, links connected at one end to said flap valves, a crank shaft provided with a crank within said pipe on which the other 5 ends of said links are mounted, an outwardly projecting portion of said crank shaft on which is secured an operating lever, a weight mounted on said lever, a flexible connection, one end of which is secured to 10 said lever, guide sheaves for said flexible

connection, and means for securing the other end of said flexible connection near the front of said furnace.

In testimony whereof I hereunto affix my signature in the presence of two witnesses. 15
